UNITED STATES PATENT OFFICE.

HAZLETON LAKE, OF SHELBOURNE, VERMONT.

COMBINED WASH-BOARD AND CLOTHES-POUNDER.

SPECIFICATION forming part of Letters Patent No. 268,246, dated November 28, 1882.

Application filed September 11, 1882. (Model.)

To all whom it may concern:

Be it known that I, HAZLETON LAKE, a citizen of the United States, residing at Shelburne, in the county of Chittenden and State 5 of Vermont, have invented new and useful Improvements in Wash-Boards, which I denominate a "Combined Wash-Board and Clothes-Pounder," of which the following is a specification.

10 To the common domestic wash-board, consisting usually of a frame carrying a ribbed or fluted surface, over which clothes are rubbed in the wash-tub, I attach a clothes-pounding chamber or cup, whereby the laundress may 15 wash the clothes by pounding, as with a clothes-pounder, and use, when necessary, the ribbed surface of the board to rub the clothes.

In the accompanying drawings, Figure 1 represents a view in perspective of a wash-board 20 provided with a clothes-pounder; Fig. 2, a section lengthwise the pounding-chamber; Fig. 3, a cross-section of the same; and Fig. 4 represents a section showing openings, in connection with suction-valves, which I may use.

25 I provide the ordinary domestic wash-board with the clothes-pounding chamber A, which in the example shown is simply a rectangular metallic box, open at the top and fastened to the head-bar B of the wash-board. With this 30 construction the laundress may reverse the position of the wash-board, and, seizing it by the legs, pound the clothes after the well-known manner of using suction-pounders, and may use the ribbed surface of the board as 35 ordinarily for removing obstinate stains.

I do not confine myself to any particular form of pounder or cup or to any particular way of fastening it to the wash-board, as these 40 can be changed in many ways without departing from the spirit of my invention; nor do I confine myself to the use of metal in the construction of the pounder, as it may be of any material suitable to the purpose. It should be made stout enough to support the weight 45 of the laundress as she bears against it when using the device as a wash-board in the usual manner. I have, however, shown two ways of fastening the pounder or cup to the wash-board—one when the pounder-cup is a box or 50 chamber with a bottom, which consists in passing screws α through the wash-board head, as in Fig. 2, the other, when the wash-board head forms the bottom, by lapping and nailing

the side parts to the wash-board, as in Fig. 1. I may use the construction shown in Fig. 4, 55 wherein passages b are bored vertically from the bottom of said chamber or cup downward and meet holes c , pierced through the wash-board head. I cover the passages b in the cup-bottom by flap-valves d , so that as the 60 pounder descends the valves close and as it ascends the valves open; but the pounding device is complete without this.

I am aware that clothes-pounders are old, and I do not lay any claim whatever to any 65 particular construction of pounder, but make them of any suitable construction or form. A device for pounding clothes, however, has never, to my knowledge, been attached to a wash-board.

70 It will be readily understood that the operator has perfect control over this device when pounding the clothes, as there are two handles for grasping. The dirt is forced from the clothes as the pounder descends, and drawn 75 from the clothes as it ascends, and as this latter movement takes some little force the two legs or handles are the most convenient means for withdrawing the device. The improvement does not add materially to the cost of a wash-board, and pounders or cups may be made 80 separately and applied to any ordinary wash-board; or the cup may consist of a chamber formed of the wash-board head itself. The pounding cup or chamber is also convenient as 85 a pocket for the soap.

I may also mention that the pounding-chamber may be formed at the bottom of the wash-board by nailing sides across the legs and utilizing the inner parts of the legs as the 90 ends or short sides of the pounding-chamber.

I claim—

1. A washing-board provided with a clothes-pounding chamber or cup at one end. 95
2. A washing-board provided with a clothes-pounding chamber or cup, A, at one end and air-passages b b c c and valves d d , substantially as and for the purpose described.

In testimony whereof I have hereunto set my hand in the presence of two subscribing witnesses.

HAZLETON LAKE.
